UNITED STATES PATENT OFFICE.

ZEBULUN S. FLOYD, OF BALTIMORE, MARYLAND.

COMBINATION SHOE BOX AND COSTUMER.

Application filed May 20, 1922. Serial No. 562,307.

To all whom it may concern:

Be it known that I, ZEBULUN S. FLOYD, a citizen of the United States, residing at Baltimore, in the city of Baltimore and 5 State of Maryland, have invented certain new and useful Improvements in a Combination Shoe Box and Costumer; and I do hereby declare the following to be a full, clear, and exact description of the invention, such as will enable others skilled in the art to which it appertains to make and use the same.

This invention relates to a combination shoe box and costumer.

15 One particular object is to provide a construction of simple, neat, durable and compact form on which the clothing and shoes of the wearer may be placed, rather than on the floor of the bed room and chairs and the 20 like to add to the tidy appearance of the room.

Another object is to provide in a construction of this character a container adapted to be pushed or rolled from place to place 25 in combination with a foot rest or support and normally held in an elevated position to prevent interference with the rolling of the costumer and depressible to prevent such rolling incidental to actual use.

30 Still another object is to provide a portable construction having a foot rest or equivalent means normally held in an elevated position by a closure for the container when in a closed position and adapted to 35 contact with the floor when the closure is in an open position.

Additional objects and advantages will become apparent from a consideration of the description following taken in connection 40 with the accompanying drawings illustrating one practical embodiment.

In said drawings:—

Figure 1 is a front elevation of the improved device;

45 Figure 2 is a side elevation;

Figure 3 is a central vertical sectional view particularly through the container on the line 3—3 of Figure 2 showing the closure of the container in closed position;

50 Figure 4 is a view similar to Figure 3 showing the closure in an open position; and

55 Figure 5 is a plan view particularly showing the container and having the closure thereof in open position; and

Figure 6 is a detail perspective view of the foot rest.

Like reference characters designate like or similar parts in the different views.

In reducing the invention to practice, a 60 box or container is provided as at A which may be of any desired shape, preferably closed at its sides, ends, and bottom, and partly closed at its top by a wall 10 to which a plate or closure 11 is hinged as at 65 12 to complete the closing of the top and which closure 11 preferably assumes an inclined position as shown, with the end walls appropriately cut away as at 13 to accommodate such disposition. Casters or roll- 70 ers 14 may be appropriately secured to the bottom wall of the casing or container A in order that it may be readily moved over a floor.

Rising from the container or supporting 75 body A is a staff or post 15 which is provided with hooks or equivalent suspending means in any desired number as at 16, in order to constitute a costumer.

Disposed, for instance at an angle as 80 shown and within the container A is a shelf 17 upon which brushes, cloths, or other media used for instance in the cleaning or polishing of shoes may be placed. Said shelf 17 projects forwardly away from the 85 post 15 beyond the hinges 12 and at 18 has an upper section 19 of a foot rest or support 20 pivoted thereto. Foot rest or support 20 is completed by a leg section 21 which may be rigid with the section 19 or pivoted thereto 90 as at 22 and slideable through an opening 23 in the bottom of the container so that it may contact with the floor or surface supporting the rollers 14.

At the rear end of the section 19 a knob or 95 projection 24 may be provided which is overlapped by the closure 11 and adapted to extend into the path of closing movement of said closure 11 so that the closing movement of closure 11 will abut the knob 24, tilt the 100 same on its pivot 18 and raise the support or foot rest 20 and leg 21 out of contact with the floor.

In using the device or apparatus, various 105 articles of clothing and the like may be suspended on the hooks 16 while the shoes or other articles may be placed within the container A. When the closure 11 is in closed position, its contact with the knob 24 causes the foot rest or support 20 to assume a posi- 110

- tion with the lower end of leg 21 above the floor or supporting surface so as not to interfere with free rolling of the article from one position to another as may be desired.
- 5 When the closure 11 is raised, the weight of the foot support or rest at the leg end 21 is sufficient to cause the leg 21 to move downwardly into contact with the floor as the knob 24 is free to move upwardly inasmuch
- 10 as closure 11 has been swung out of engagement therewith. In this position, the section 19 is exposed so that the shoe while on the foot may rest thereon and be supported as while lacing or fastening the shoe or
- 15 while brushing or polishing it. The pressure of the leg incidental to the support of the same and shoe on the section 19 causes the leg 21 to frictionally bind on the floor so as to prevent rolling or undue movement
- 20 of the article by the shoe when thus supported.

As merely one practical embodiment has been illustrated and described, it is to be understood that changes in the details may 25 be resorted to provided they fall within the spirit and scope of the invention.

Having thus described the invention, what I claim as new is:

1. An article of furniture having a foot support pivoted thereon and provided with 30 means engageable with a supporting surface whereby pressure on said foot support tends

to hold the article stationary, a plate hinged-
ly carried by said article of furniture, and
said support being operable through contact 35
with the plate to withdraw said means from
the supporting surface.

2. An article of furniture having a foot support provided with means thereon engageable with the supporting surface for the 40 article to hold the same stationary, a movable plate, and said support when in contact with said surface extending into the path of movement of said closure plate whereby the 45 foot rest is operative through contact with the plate to withdraw said means from the supporting surface.

3. An article of furniture having a container, a closure plate movable relatively thereto, a shelf within the container, a foot 50 support pivoted on said shelf and provided with means at one end engageable with the supporting surface for the article to hold the same stationary, and means adjacent the other end of said support operative through 55 contact with the closure plate to withdraw the first mentioned means from the supporting surface.

In testimony whereof I affix my signature in presence of two witnesses.

ZEBULUN S. FLOYD.

Witnesses:

JOHN W. BACKER,
S. ROBERT MARTIN.
